UNITED STATES PATENT OFFICE

MARY I. GUZAK, OF NEW YORK, N. Y., ASSIGNOR TO ASSOCIATED MERCHANTISING CORPORATION, OF NEW YORK, N. Y., A CORPORATION OF NEW JERSEY

DESIGN FOR AN ENSEMBLE DRESS

Application filed October 30, 1931. Serial No. 41,576. Term of patent 3½ years.

To all whom it may concern:

Be it known that I, MARY I. GUZAK, a citizen of the United States and a resident of New York city, borough of Manhattan, in the county of New York and State of New York, have invented the new, original, and ornamental Design for an Ensemble Dress, of which the following is a specification.

Reference is had to the accompanying drawings, forming part thereof, wherein—

I claim:

The ornamental design for an ensemble dress substantially as shown.

MARY I. GUZAK.
